UNITED STATES PATENT OFFICE.

ERNEST H. FREY, OF WILLOUGHBY, OHIO.

RECEPTACLE FOR TYPE-HOLDERS.

1,106,553.

Specification of Letters Patent. Patented Aug. 11, 1914.

Application filed November 6, 1911. Serial No. 658,754.

To all whom it may concern:

Be it known that I, ERNEST H. FREY, a citizen of the United States, and resident of Willoughby, in the county of Lake and State of Ohio, have invented certain new and useful Improvements in Receptacles for Type-Holders, of which I hereby declare the following to be a full, clear, and exact description, such as will enable others skilled in the art to which it appertains to make and use the same.

The objects of the invention are to provide a receptacle for storing the type holders for the addresses employed in an addressing machine. This receptacle is designed to retain the type holders in either a vertical or horizontal column, for storage, and is provided with spring retainers at the lower end which support the column of cards until the receptacle is placed in vertical position in the addressing machine, when by releasing the spring retainers the type holders will fall by gravity upon a conveyer which carries them to the printing position. The receptacle is also designed to receive the type holders after the impression has been taken therefrom, and for this reason is open at the upper end, so that these receptacles can be used interchangeably in either position. The receptacle is also provided with removable guard rods arranged longitudinally thereof just within the edges of the side walls of the receptacle, so that the type holders can be held in place when the receptacle stands vertically, but will be accessible for inspection or change in order of printing or removed if desired, when the receptacle lies in the horizontal position.

The invention also includes a removable spring keeper or follower which is inserted between the side walls of the receptacle and retains the type holders in place so that only a few or a large number of them can be retained in place without disorder. An important feature of advantage in the receptacle is its adaptability to be kept in the manner of a drawer in a suitable case, so that several series of addresses can be filed away for use, each receptacle containing a separate series of address cards or type holders for any use required. The case in which these drawer receptacles is stored usually accompanies each addressing machine, and as many series of addressing type holders can be used as may be desired. The

type holders are provided with a designating or initialed card which projects through the open central space and can be readily seen and found when any alterations in the order of the type holders or the removal of one of them is desired.

The invention also comprises the combination and arrangement of parts and construction of details as hereinafter described, shown in the accompanying drawings and specifically pointed out in the claims.

In the accompanying drawings Figure 1 is a front view of the device; Fig. 2 is a side elevation thereof; Fig. 3 is a longitudinal section of the open end of the receptacle showing one of the retaining rods and its socket; Fig. 4 is a similar section of the opposite end showing one of the spring pressed rods; Fig. 5 is a transverse section of Fig. 2 looking toward the open end; Fig. 6 is an end view showing the type holder retaining springs.

In these views A, A' are three-sided frame portions of rectangular shape arranged at the ends of the receptacle. B, B, are angular plates secured to these frame portions, and connecting them to form side walls b, and ledges b', b', by means of which the type holders are retained in the receptacles when in the vertical or horizontal positions. The ledges b', b', thus form back or bottom strips as may be required for the receptacle. The type holders rest upon the ledges b', b', when the receptacle is lying in the horizontal position, or the receptacles can be stored on edge as shown in Figs. 5 and 6. To retain the type holders in position so that they will not fall out of the open front P of the device rods C, C, are inserted in the oppositely placed sockets D, D' in the frames A, A', and are retained in place by means of the springs E, E, so that they can readily be removed to withdraw the type holders. Retaining springs G, G at one end of the receptacle prevent the type holders from falling out at that end. And a removable spring follows F, is placed in the receptacle to secure them at the other end. In this form of construction the front and back are left completely open through the central part, the open back permitting of the introduction of mechanism in the machine from the rear, to support the type holders and to lower them gradually into the receptacle as shown in an ac-

companying application Ser. No. 658,753, filed Nov. 6, 1911, for letters patent on an addressing machine.

In this machine the receptacle full of type holders is set vertically over an opening as O through which the type holders are permitted to fall to the conveyer which carries them to the printing position, and when put into place the retaining springs G, G which are provided with inwardly turned forked extremities H, H, are formed outwardly automatically by means of solid wedges I, I, upon the machine, and shown in dotted lines in Fig. 1, and in this manner the type holders are immediately released. These wedges follow grooves J, J in the outer edges of the frame A' and the bottoms of the grooves are correspondingly inclined. The wedges I I engage the grooves J J simultaneously with the pushing out of the springs G. These forked springs have longer sides which are secured to the outer sides of the side walls at K, K, and the forked ends which lie on opposite sides of the grooves J—J are separated sufficiently by the wedges I, I, to give a clear path to the type holders. The type holders T are provided with the distinguishing cards t which project through the front opening P and thus make every type-holder accessible for removal or change of position, similar to a card filing drawer or case.

Having described the invention what I claim as new and desire to secure by Letters Patent is:

1. In a receptacle for a series of type holders, a three sided frame member at each end, angle plates comprising side and bottom portions connecting said frames, and arranged to provide an open central space between them extending from frame to frame, means for detachably retaining the type holders, said retaining means located at one end of the receptacle, the other end thereof being open, and longitudinal retaining rods spaced from said side plates and removably inserted in said frame members.

2. In a receptacle for type holders in com-

bination, three sided frames at the upper and lower ends thereof, connecting plates for said frames having side and rear portions, 50 said rear portions being spaced apart to provide a central longitudinal opening, said lower frame being provided with longitudinal grooves on its outer sides, and spring retainers secured to said side portions, said 55 spring retainers being provided with inwardly turned forked extremities, the forks passing on each side of said grooves whereby a means for spreading said spring retainers can be inserted in said grooves. 60

3. In a receptacle for type holders, said type holders having projections on which designating characters are displayed, a frame at each end of said receptacle, angle strips connecting opposite sides of said 65 frames and forming sides and back portions, said frames being three sided to permit the passage of said projections on said type holders, removable retaining means for preventing the type holders from falling out of the open side of said receptacle, and spring 70 retainers at one end of the receptacle, the other end being open.

4. In a receptacle for type holders, side and spaced rear walls, three sided connecting 75 members at the ends of said walls providing an unobstructed opening on the fourth side, spring retainers at one end of said receptacle, and removable means for preventing the said type holders from falling out of the 80 said opening.

5. In a receptacle for type holders, a hollow body open at each end and on one side, and a movable retaining device adapted to prevent the type holders from falling out of 85 the open side, a movable follower in one end of the receptacle and movable keepers at the other end.

In testimony whereof, I hereunto set my hand this 23d day of May, 1911.

ERNEST H. FREY.

In the presence of—

L. R. CANFIELD,
Wm. M. MONROE.
